UNITED STATES PATENT OFFICE.

GUY W. FERDON, OF CRESKILL, NEW JERSEY.

COLLAPSIBLE FOLDING STOVE.

1,300,594.

Specification of Letters Patent. Patented Apr. 15, 1919.

Application filed January 28, 1918. Serial No. 214,150.

To all whom it may concern:

Be it known that I, GUY W. FERDON, a citizen of the United States, residing at Creskill, county of Bergen, State of New Jersey, have 5 invented certain new and useful Improvements in Collapsible Folding Stoves; and I do hereby declare the following to be a full, clear, and exact description of the invention, such as will enable others skilled in the art 10 to which it appertains to make and use the same.

My invention relates to collapsible folding stoves of a type that may be easily knocked down or separated, and one which is adapted 15 to the burning of fuels of widely different character.

My stove is adapted to the burning of kerosene or similar fuel, gas, and to alcohol in either liquid or solid form.

20 My stove embraces devices whereby the position of the burning fuel with reference to the grate, may be adjusted by moving them closer together or farther apart to adapt the device to be used to the particular 25 fuel of the moment.

Particularly marked conditions of cost between oil and denatured alcohol may be such that under some circumstances, or in some 30 localities, one may be preferable or obtainable, and under other circumstances or in other localities, the other. Also my device may be employed in connection with gas, either natural or artificial.

I adapt my burners to the use of any of 35 these fuels by very simple means, which will be explained in detail.

My stove is adapted for ready cleansing and attention, and is readily collapsible, which is of great value in saving weight and 40 cubic measurement for shipping and transportation. The stove may also be shipped set up, if desired.

In the accompanying drawings like figures of reference indicate like parts, and in these 45 drawings:

Figure 1 is a perspective view of my stove showing the general arrangement when kerosene is burned.

Fig. 2 is a view of the same stove adapted 50 to use alcohol.

Fig. 3 is a part sectional view of the stove with the kerosene burning device.

Fig. 4 shows details of the movable shelf.

Fig. 5 is a bottom plan view of one of the chimneys.

Fig. 6 is a view of one of the burners showing the wick.

Fig. 7 shows the arrangement of my kerosene burner by which it is adapted for burning alcohol, and also for burning solid 60 alcohol.

Fig. 8 is a perspective view of a cap which I use.

Fig. 9 is a sectional view of the same cap, said cap being used in connection with the 65 kerosene burner.

Figs. 10, 11 and 12 are diagrammatic views showing the position of the shelf in outline when various fuels are used.

Fig. 13 indicates the shelf removed, and 70 Fig. 14 is a perspective view of the bracket or shield detached.

In the drawing, 1 indicates the top plate or grate plate of my stove provided with the grates 2, tank 3, fuel supply pipe 4, burners 75 5, and chimneys 6. The device is provided with a fuel shelf 7, which is shown supplied with bolts 8. These bolts are movable or 80 slidable in slots 9 in the standards or legs 10 of the frame, whereby the fuel shelf may be readily set to any height within the slots, the bolts being supplied with milled nuts 10' for ready adjustment or removal.

The tank 3 may be removed at 11 by unscrewing the nutted coupling, and attachment be made to a gas supply, if desired. 85 The tank 3 is of the usual type, and is provided with the usual valve 12; when the tank is inserted in place, this valve 12 discharges into a lower fuel tank 13 and is connected by 90 means of the pipe 4 with the burners. This is a usual construction, and the tank may also be provided with a projection 14, so that when it is inserted it may rest upon said projection and be kept steady. The two tanks 95 are supported by a bracket 15 and by the fuel supply pipe. When the tank is in the lowest position, that is, when kerosene is being

burned, two bolts 16, which connect the bracket to the apron or cross piece 17 between the two legs on the right hand, are passed through registering upper holes in the bracket and cross piece, and these aid in securing the tank in rigid position. When in 10 this position, if the tank is supplied with 10 fuel in the usual way, as soon as the valves 18

are opened fuel begins to pass to the burners, which I show here as the burners of a vapor burning stove, or, as it is sometimes called, of a "blue flame" stove, a match being applied 5 and the burners heated in the usual manner the chimneys 6 soon transmit the usual hot blue flame to the grates 2.

I provide the legs 10 with suitable marks 20, to indicate the desired height for different fuels. This aids in easy adjustment, and when the shelf is adjusted to the lowest mark 20, the stove supplies the greatest amount of heat to the grates 2, the stove then behaves as an ordinary blue flame kerosene 15 stove, and has all the properties of such a stove in addition to certain other features to be discussed later.

If it is desired to use commercial or denatured alcohol, the fuel shelf is raised and 20 set in the slotted legs at the upper mark 20, and as indicated in Fig. 4. If the stove has been set previously for use with kerosene, the bolts 16, which affix the lower fuel tank of the bracket to the side of the piece 17, are 25 removed so that the fluid shelf, burners, and supply tank move in unison and to their new level of adjustment for the use of fluid alcohol. The adjustment of the shelf at the upper 30 mark 20 is such that when fluid alcohol is placed in the upper reservoir 3, and this placed upon the lower feeding tank, the alcohol burns with a clear blue flame of intense heat.

The only change from the use of the stove 35 as a kerosene oil blue flame stove to a liquid alcohol blue flame burning stove, is the new adjustment, above indicated, to the upper mark 20, and the removal of the usual asbestos wicks or kindlers indicated in Fig. 6 40 by the zig-zag circle and in section in Fig. 7 and the chimneys 6; no admixture of air through the combustion tube being needed when alcohol is used because the adjustment of the upper mark 20 provides a perfectly 45 burning blue flame when cooking vessels of any kind are used over the flame on top of the grates. If the burners be set substantially lower, the resulting flame, if alcohol be used, is not a proper flame; in fact it is a 50 streaky white or yellow flame, and does not give the heat of a blue flame because the proper line of adjustment is lacking.

The means for turning off and on the liquid alcohol is the same as in the case of 55 kerosene. When the tank is moved up to the new or upper adjustment, the protecting shield or bracket 15 attached to the lower tank, of course moves with it and appears above the top of the stove, where it serves 60 to shield the flame and also to protect the tank from the flame.

A second set of holes for the bolt 16 is provided to secure the new adjustment of the tank, the bolts passing through the same 65 holes in the member 17 but through different

holes, of course, in the bracket 17, as indicated in Fig. 2. It will be noted that the shield or bracket is provided with an offset or step at 21, to enable the bracket or shield to accommodate itself to the overlapping 70 top, as seen in Fig. 3.

The so-called solid alcohol put out by many different manufacturers, is canned in receptacles or cans of practically the same diameter and height. When I use these cans 75 of solid alcohol the fuel tanks may or may not be removed. In changing the stove or fuel shelf for use with solid alcohol, the said shelf is moved to the intermediate adjustment 20 and set there; but, of course, it may 80 be moved to any other intermediate point that may seem best to suit the height of the particular can used. The center cap pieces 22 of the burners are removed from the tops of the burner cups. This leaves a cavity 85 or hole in the center of each burner into which the can may be slipped, and in which it fits or rests with sufficient adaptation. The can reaches its proper seat when it rests upon the Y-shaped fuel supplying tubes 90 23 of the burner cups, and I have indicated in Fig. 7, by dotted lines, such a can 24.

I have also indicated by dotted lines 25, in Fig. 4, the position approximately of the shelf when solid alcohol is burned, the same condition is indicated in Fig. 2. The V-shaped or divergent tubes 23 furnish a secure base for the bottom of the can of alcohol. If cans too large in diameter to go through the opening in the burner should be used, 100 the shelf may be set lower by re-seating the adjusting bolts in a manner that is obvious.

Differently "solidified" alcohols burn with different flames, depending upon the nature, kind, or quantity of the agents used 105 in solidification. Some give higher flames than do others, and the proper adjustment should, of course, be made accordingly. A can of solidified alcohol also, when partially used, does not give as good a flame as at the beginning, and adjustment should be made for this. I may provide holes in the flange at the top for bolts 16.

My stove is also adaptable for use with the cubed alcohol, that is, alcohol solidified but not in cans, these cubes being purchasable almost anywhere. The cubes are placed directly on top of the center of the cap piece 22 in the center of the burner, the fuel shelf having been previously properly adjusted. 115 This cube burns with a clear blue flame, and other similar cubes may be added from time to time as needed, as several may be placed on at one time.

If the stove be employed on, say, a camping trip on which no oil or other suitable fluid, cube, or solid alcohol is obtainable, the stove may then be used as a wood burning camp stove by removing entirely the fuel shelf and reservoir, and simply setting the legs in 120 125

the sod or dirt and then applying a wood fire beneath the stove. This does not injure the stove for any of the other uses.

It will thus be seen that I have devised a 5 stove which is generally adaptable to use with fuels of various kinds, and which can be readily and quickly adjusted to the use of the particular fuel employed by the greenest tyro without danger or possibility 10 of going wrong, the adjustments for the fuels supplied in bulk, namely, alcohol and kerosene, being substantially fixed at definite points, and the adjustment for canned alcohol and cubed alcohol being left available 15 at will, as also may be said of the use of the stove for wood.

In addition to the features pointed out herein it should be noted that the stove is made readily detachable by the use of bolts 20 25, so that it may be knocked down if desired.

Having thus described my invention, what I claim as new and desire to secure by Letters Patent is:

25 1. In a knock-down stove, in combination, a hot-plate, a burner shelf adjustable with reference to said hot plate, a burner on said shelf, a tank and connecting tubes, a chimney for said burner, whereby air is mixed 30 with the gasified fuel when kerosene or similar hydrocarbon is used, said chimney being removable and the burner shelf being adjustable nearer the hot plate whereby said burner and stove are adaptable for the use 35 of a direct burning fuel in said tank, and the fuel feeding tubes adapted to form supports for holding cans of solidified alcohol when solidified alcohol is used.

2. In a liquid fuel stove, in combination, 40 a frame, a top plate, a burner, said burner provided with means whereby it may be adapted for use with fuels of different kinds, a burner shelf adjustable on the frame, below the top plate, said shelf being movable to 45 positions defined on the frame to adapt the stove to the use of various and definite fuels, a feed tank connected to said burner, and adjustable with the burner to position above the top plate for fuel of direct burning kind 50 and below the hot plate for fuel suitable for vaporizing before burning, the lowest adjustment providing space for a fuel gasifying device between the burner and the plate, and a shield for the tank, adjustable with the 55 tank, said shield serving when the tank is above the level of the top plate, to protect the tank from the heat of the burner.

3. In a stove, in combination, a frame, a 60 hot plate, grates therein, a fuel shelf adjustable on the frame to marks determined properly as to the proper positions for kerosene, for liquid alcohol, for solid alcohol and for gas, burners on said shelf, said burners having means whereby they may be made adaptable for use with fuels of different kinds, a

supply pipe leading to said burners, and a fuel tank removably coupled to said supply pipe whereby the tank may be uncoupled and the stove connected to a gas supply for use as a gas stove, substantially as described. 70

4. In a liquid fuel stove, in combination, a top plate, a removable and adjustable burner shelf below said plate, kerosene burners on said shelf, kindlers and chimneys for said burners, the construction of said burners being such that by removal of said kindlers and chimneys they may be converted into burners for fuels of other kinds, a fuel tank communicating with said burners, slots in the frame of the stove, and supports connected with the shelf, adjustable in said slots, whereby said shelf may be set near the top of the plate for burning one kind of fuel or at other distances for burning fuel of other kinds. 80 85

5. In a liquid fuel stove, in combination, a top plate, a removable and adjustable burner shelf below said plate, kerosene burners on said shelf, kindlers and chimneys for said burners, the construction of said burners being such that by the removal of said kindlers and chimneys the said burners may be converted into burners for fuels of kinds different from kerosene and into supports for holding solid fuel, and means whereby the shelf may be set at proper distances for burning fuels of various kinds. 90 95

6. In a stove for burning fuel, in combination, a top plate, a burner support, a kerosene burner having a kindler or wicks and chimney, on said support, said burner being provided with means whereby by the removal of or adjustment of certain parts it may be converted into a burner for using kerosene, into a burner for using liquid alcohol, into a burner for using solidified alcohol in cans, into a burner for using cubed or lumped alcohol, into a burner for gas, and means whereby the burner support may be set at varying heights to meet the requirements for burning the different fuels. 100 105 110

7. In a knock-down stove, a hot plate, slotted legs detachably connected to said plate, a burner shelf adapted to be adjusted with reference to said hot plate, a burner, said burner provided with parts by the removal or adjustment of which it may be converted into a burner for fuels of different kinds, a bracket for supporting a fuel reservoir, said brackets removably attached to 115 said legs, and a fuel reservoir removably attached to the bracket and burner shelf. 120

8. In a stove for burning fuel, in combination, a hot plate, a support to which said hot plate may be attached, means for supporting 125 fuel burners in a plane substantially parallel with said hot plate, said burner supporting means being adjustably movable perpendicularly below the hot plate and up and down the hot plate support, whereby proper 130

- adjustments for meeting burning requirements of differing fuels, or any one of them, may be made at different heights, and connecting means between the means for supporting the burners and the hot plate support whereby the burners and burner supporting means may be moved to or from a

determined position in a line substantially parallel with the hot plate and when so moved to their proper position for burning, 10 may be removably engaged to the hot plate support.

In testimony whereof, I affix my signature.
GUY W. FERDON.
